UNITED STATES PATENT OFFICE.

ANDREW PETER ANDERSON, OF MILBURN, UTAH.

ROTARY ENGINE.

SPECIFICATION forming part of Letters Patent No. 723,226, dated March 24, 1903.

Application filed August 20, 1902. Serial No. 120,309. (No model.)

To all whom it may concern:

Be it known that I, ANDREW PETER ANDERSON, a citizen of the United States, residing at Milburn, in the county of Sanpete and State of Utah, have invented certain new and useful Improvements in Rotary Engines; and I do hereby declare the following to be a full, clear, and exact description of the invention, such as will enable others skilled in the art to 10 which it appertains to make and use the same.

My invention has relation to rotary engines; and it consists of certain novel features of combination and construction of parts, the preferred form or materialization whereof 15 will be hereinafter specifically set forth, and pointed out in the claims.

The object of my invention, among others, is to provide an engine of the character specified which will reliably drive the piston in a 20 continuous rotation, thereby enabling the pounding due to reciprocatory motion, as is common with the ordinary steam-engine having a longitudinally-moving piston, to be completely eliminated.

25 A further object, among others, is to provide very simple though reliably efficient devices adapted to confine the live steam and concentrate the force thereof directly upon the forwardly-moving part of the rotary piston 30 ton and also to provide for the free exhaust of the steam in advance of the moving extension of the piston, said objects being accomplished, as will be hereinafter specifically set forth, by the employment of a minimum number 35 of parts or devices.

A further object of my invention is to so form and mount the controlling-valves for the live and exhaust steam chambers that said valves will be operated at the expense of a 40 minimum amount of friction and with the assurance that the line of separation between the live and exhaust steam will be perfectly drawn.

Other objects and advantages will appear 45 from the following specification, reference being had to the accompanying drawings, which are made a part of this application, and in which—

Figure 1 is a top plan view of my rotary engine complete. Fig. 2 is a front elevation thereof. Fig. 3 is a similar view to that presented in Fig. 2, showing the cylinder-head

and certain parts carried thereby removed. Fig. 4 is a central vertical sectional view on line *w w* of Fig. 1. Fig. 5 is a central sectional view as seen from line *x x* of Fig. 2. Fig. 6 is a perspective view of the piston and the driving-shaft to which it is secured or with which it is integrally formed. Fig. 7 is a sectional view on line *y y* of Figs. 2 and 3. Fig. 8 is a sectional view of the piston removed from the cylinder as seen from the dotted lines *s s* of Fig. 4. Fig. 9 is a sectional view as seen from the dotted line *t t* of Fig. 4, while Fig. 10 is a perspective view of 65 one of the valves removed from its contiguous parts.

In referring to the various details of my invention and coöperating accessories numerals will be employed, the same numeral referring to a similar part throughout the several views.

The numeral 1 designates the base member, which may be of any preferred form or size deemed most suitable to meet the requirements and is provided with standards 2 and 3, the former standard being designed more especially for the purpose of carrying the cylinder or housing proper, 4, while the standard 3 is provided at its upper end with a boxing adapted for a purpose hereinafter more clearly set forth. The cylinder 4 is provided at each end with a suitable head 5, said head having, as is common, a diametrically-disposed extension or sleeve designed to co-operate with the usual stuffing-boxes 6 and 7, said boxing providing suitable bearings for the piston-shaft 8 and also preventing the escape of steam.

Integrally formed with the shaft 8 or otherwise rigidly attached thereto is the rotary piston 9, said piston being substantially disk-like in form and is adapted to rotate within the casing or cylinder 4, as is common. At diametrically opposite points of the peripheral face of the disk-like piston 9 I provide the swells or webs 10, the extreme outer surface of each of which fits snugly against the inner face of the casing, thereby practically dividing the space between said webs or extensions 10 into two separate and distinct compartments or semi-annular spaces.

By reference to Fig. 6 and other views it will be observed that each of the webs 10 is

so formed upon one side as to be provided with the extension 11, the outer surface of which presents an inclined plane extending from the periphery of the piston to the extreme outer end of the web 10, the surface of the extension 11 gradually merging into the extreme outer surface of said web.

Upon the opposite side of the webs 10 from that occupied by the extension 11 I provide the rib or web reinforcing section 12, which subserves a purpose hereinafter more clearly pointed out.

The piston 9 is provided upon each side with annular grooves or ways 13 and 14, the former groove providing a path through which the live steam gains access to and drives the piston, while through the annular groove 14 the exhaust-steam is permitted to pass out from the space in advance of the web 10 and its coöperating inclined reinforcement 11, as will be hereinafter more clearly specified.

It will be observed by reference to Figs. 8, 9 and other views that the piston is provided with properly-located inlet-ports 15, through which the live steam is introduced into the semi-annular space in advance of the web 10, while the exhaust-port 16, communicating directly by proper bearings or branches with the annular way 14, affords a path or roadway through which the exhaust-steam is discharged into the open air without exerting any of its expansive force as a back thrust upon the extension or web 10 of the piston.

In order to successfully operate my improved rotary engine, I have provided the spring-controlled sliding valves or steam-holding devices 17, said valves being mounted in bearings 18, located at proper points around the periphery of the cylinder or casing, as will be more clearly seen by reference to Fig. 4. Each of the said valves is provided with properly-formed channels 19, the object of the channels being to permit the steam to pass above the main or body portion of said valve, thus insuring that the steam will practically surround said part, and thereby distribute or equalize the pressure and permit the valve to more freely reciprocate in the performance of its office. The valve 17 is so formed that it will be provided with a suitable stem 20, which is preferably round in cross-section, said stem being adapted to pass through a properly-located stuffing-box in the upper end of the valve-seat or bearings 18, the extreme upper end of said stem being provided with a notch or recess into which the free end of the arm 21 extends, while the opposite end of said arm is pivotally mounted upon the properly-located bracket 22, said bracket being in turn firmly secured in place in any preferred manner, preferably to one of the cylinder-heads or to the gland or diametrical extension carried by said head, as will be more clearly observed by reference to Fig. 7. The free end of the arm 21 is normally held in contact with the end of the stem 20 of the valve 17 by means of a suitable

spring 23, the outer end of which is provided with the loop-section 24, adapted to encircle a contiguous part of the arm 21, while the inner or lower end takes around and is secured by the free end of the threaded anchoring-bolt 25, said bolt being secured in any preferred way to a contiguous part of the bracket 22.

It will be observed that each of the arms 21 is provided, preferably, with the plurality of properly-located notches or recesses 26, into any one of which the loop 24 may be caused to take, thereby definitely locating the force to be brought to bear upon said arm by said spring and enabling the operator to readily graduate the degree of tension to be sustained by said arm and applied thereby to the valves 17, thereby insuring that each of the valves will be held in intimate and close contact with the peripheral face of the piston and caused to ride over the peripheral face of the piston upon the inclined surface 11 and across the end of the web 10, and thence passing down the inclined surface of the web 12 into contact again with the face of the piston proper, which latter, it will be observed, is concentric to the shaft upon which said piston is located. A greater or less degree of tension may also be given to the spring 23 by means of the butt or nut 27, which is adapted to be screwed up or down upon the bolt 25, thus decreasing or increasing the tension upon the said spring 23. The elongated end of the piston-shaft 8 passes through the boxing upon the standard 100 3 and carries at its outer end the belt or driving pulley 28, said pulley being rigidly keyed or otherwise secured to the said shaft.

In operation the steam is injected into the cylinder 4 through a suitable pipe 29, said pipe registering with the orifice 30, said orifice in turn registering with the annular channel 13 of the piston 9. The steam passes thence through the ports 15 into the chambers 31 and 32, formed by the webs 10 and two of the valves 17. Owing to the fact that the valves 17 are held normally down against the periphery of the piston 9, the live steam meets with a resistance in this direction, so that by the expansion of said steam the piston 9 is caused to rotate by the expanding steam pressing against the webs 10. Immediately after the live steam enters the chambers 31 and 32 the exhaust-steam in the chambers 33 and 34, formed between the valves 17, is permitted to enter the exhaust-ports 16, from thence into the channels or grooves 14, and into the discharge-pipe 35.

It will be understood that when the piston 9 turns another quarter the chambers 33 and 34 will form the live-steam chambers and the chambers 31 and 32 will form the exhaust-steam chambers. It will also be understood that the valves 17 will alternately ride up on the inclined surface of the projection 11, thus permitting the webs 10 to pass the said valves 17, the inclined web 12 permitting the valves to gradually descend on the opposite side of the webs 10, thus allow-

ing the valves to be raised and lowered without any undue jar or friction. The valves 17 are returned to their normal inward position through the medium of the pivoted arm 21 and tension-spring 23. Should it be desirable to manufacture the cylinder 4 out of soft material, friction-plates 36, of steel or other suitable hardened metal, may be inserted in the bearings 18 to afford a solid wearing-surface for the valves 17.

It will of course be understood that while I have described in the foregoing specification and the accompanying drawings what may be regarded as my preferred form of mechanical expression for my ideas and invention in rotary engines various modifications may be made in such construction and combination without materially departing from the spirit and scope of my invention, and I therefore wish to comprehend such substitutes and equivalents as may fairly appertain to the combination and construction presented.

It will be observed that the valve member 17 is reciprocatingly mounted in its seat and that steam-channels 19 are provided for the valve member, which enables the live steam to reach both sides or ends of said member, thus practically inclosing the valve within a steam-chamber and preventing the end thrust, which would otherwise strike the extreme inner end of the valve if the channels 19 were omitted. The provision of said channels also prevents the forming of a vacuum in the outer end of the valve-seat or that portion of its interior adjacent to the stuffing-box upon an inward thrust of said valve.

By the means I have herein provided, as illustrated and described, it will be seen that the rotary piston will be continuously driven, and thereby rotate the shaft in a positive manner and actuate such machinery as may be connected to said shaft through the medium of the drive-wheel 28 or otherwise. The live steam will find its way, as hereinbefore stated, first into the annular groove 13 and thence through the port 15, to be discharged immediately behind the web 10, thereby applying the expansive force of the steam upon the face of said web and insure that the piston will be rapidly rotated.

It will be further obvious that ample provision has been made for the escape or exhaust of the steam thus introduced as soon as the exhaust-port 16 has moved past the inner end of the piston 17, which latter is always held in close engagement with the peripheral face of the piston by action of the spring members 23. This operation of the

introduction of the live steam and the exhaust thereof after it shall have performed its office is continued or repeated with the rotation of the piston and the successive passing of the exhaust-ports therein of the valves 17.

Believing that the advantages and operation of my improved rotary engine have thus been made clearly apparent, further description is deemed unnecessary.

Having thus fully described my invention, what I claim as new, and desire to secure by Letters Patent, is—

1. The herein-described rotary engine, comprising a suitable cylinder or casing; a piston rotatably mounted in said casing and comprising the disk-like member 9 having the extensions or webs 10, which latter snugly engage the inner face of the cylinder and thereby divide the annular space around the piston into two parts, in combination with a plurality of valves 17; means to normally hold said valves inward and yieldingly permit the same to be forced outward by the projections on the piston whereby the piston may be supplied with live steam through annular grooves in each face thereof communicating with inlet-ports extending upon opposite sides of said webs or extensions and said steam permitted to escape or exhaust through suitable exit-ports carried by said piston all combined substantially as specified and for the purpose set forth.

2. In a rotary engine, a casing, a piston rotatably mounted therein and comprising a disk-like member having swells or webs the outer surfaces of which fit snugly the inner wall of the casing and each provided upon one side with an extension 11 and upon the opposite side with a web 12 with ports 15 leading therefrom, said disk-like portion being formed with ports communicating therewith and with exhaust-ports adjacent said extensions, spring-controlled slide-valves 17 normally engaging the annular portion of said disk and each of said valves having a channel, means for normally holding said valves inward and committing their outward movement by contact with the projections on the piston, and suitable steam supply and discharge pipes, all substantially as and for the purpose set forth.

In testimony whereof I affix my signature in presence of two witnesses.

ANDREW PETER ANDERSON.
